DIAPER

Doris B. Kennard, Tampa, Fla.

Application March 27, 1934, Serial No. 717,651

5 Claims. (Cl. 128—284)

This invention relates to diapers.

An object of the invention is the provision of a garment having a triangularly-shaped supporting and securing member which includes a central portion formed of waterproof material and supplementary attaching portions adjacent the apices, formed of non-waterproof fabric and adapted to provide attaching strips for the garment, an annular absorbent pad having a transverse opening through which one of the supplementary portions project.

A further object of the invention is the provision of a garment having a supporting and securing member which includes a central portion and an auxiliary attaching portion with an absorbent pad having portions disposed upon opposite faces of the member.

This invention will be best understood from a consideration of the following detailed description, in view of the accompanying drawing forming a part of the specification; nevertheless, it is to be understood that the invention is not confined to the disclosure, being susceptible of such changes and modifications as define no material departure from the salient features of the invention as expressed in the appended claims.

In the drawing:—

Figure 1 is a view in perspective of a garment constructed in accordance with the principles of my invention,

Figure 2 is a view in perspective of an attaching and supporting member for an absorbent pad and forming an element of the garment shown in Figure 1,

Figure 3 is a view in perspective of a modified form of the garment, and

Figure 4 is a view in perspective of another modified form of the invention.

Referring more particularly to the drawing, 40 10 designates a triangularly-shaped supporting member having a central portion 11 formed of waterproof material and auxiliary portions 12, 13 and 14 which project from the edges of the central portion 11 to provide attaching strips 45 and these strips are located adjacent the apices of the triangularly-shaped supporting member and formed of non-waterproof fabric.

An annular absorbent pad 15 has an inner face 50 16 made of any suitable fabric for forming a backing for the pad 15.

The pad, as shown at 17, is provided with a slit through which projects a tab 14.

In this construction it will be seen that the attaching strips 12, 13 and 14 are formed of any well-known fabric which is soft so that it will not in-

jure the body and that these strips can be brought around the body and connected together in any approved manner.

Referring more particularly to Fig. 3 it will be seen that a similar construction is provided in which the triangularly-shaped member 10 supports an absorbent pad 20 which has its inner face, as shown at 21, formed of any suitable fabric as a base member for the pad 20.

The triangularly-shaped member 10 has attaching strips 12 and 13 projecting oppositely from the upper portion of the said member and upon opposite sides of the waterproof material 11. It will be noted that the backing 21 in this case extends downwardly in the shape of a triangle and indicated at 22 upon the opposite sides of the member 10 and the members 22 together with the strips 14, 12, and 13 provide means for supporting the garment on a body when said strips are all connected together.

It will be noted that the pad 20 terminates short of the members 22 so that the pad is merely supported on the upper edge of the member 10.

Referring more particularly to Fig. 4 it will be seen that a further modified form of the invention is disclosed in which a sheet 25 formed of waterproof material provides the main support for a pad 26. The member 25 is provided with projecting straps 27 and 28 and these straps are oppositely disposed. Projecting from the lower end of the member 25 is another strap 29 which passes through a slit 30 formed transversely of the pad 26.

This pad is formed of absorbent material and is provided with an annular base member 31 to 35 which the pad is connected. The base member may be formed of any suitable fabric for the purpose.

It will be noted in this construction that the straps 27, 28, and 29 form the attaching means 40 for the garment and for supporting the annular pad 26.

In Figs. 1 and 4 the pads 15 and 26, respectively, are provided with slits through which the lower attaching member projects and this arrangement provides means for retaining the pad in proper position upon the supporting member.

I claim:

1. A diaper comprising a triangularly-shaped supporting and securing member consisting of a central portion formed of waterproof material and supplementary portions adjacent the apices being formed of non-waterproof fabric and adapted to provide attaching strips for the diaper, and an annular absorbing pad having an opening 55

through which one of the supplementary portions projects.

- 5 2. A diaper comprising a sheet of waterproof material having oppositely disposed attaching strips at the upper end and a depending attaching strip, an annular pad formed of absorbent material and provided with a transverse opening through which the depending strip projects, said pad being loosely and removably supported on the waterproof material.
- 10 3. A diaper comprising an annular pad formed of absorbent material, a sheet of waterproof material within the pad and attaching strips connected to the sheet and projecting outwardly from the pad in a plurality of directions.
- 15

4. A diaper comprising a pad supporting and securing member having oppositely disposed attaching strips projecting from the upper end and an attaching strip depending from the lower end, and an endless pad formed of absorbent material and provided with a transverse slit through which the depending strip projects.

5. A diaper comprising a sheet of waterproof material, attaching straps connected to opposite edges of the sheet adjacent the top portion, an elongated endless member formed of fabric receiving the sheet of waterproof material and loosely supported by said sheet, and a pad of absorbent material secured to one face of the fabric.
